UNITED STATES PATENT OFFICE.

JOSEPH A. GROEBLI, OF NEW YORK, N. Y.

BEAD-SEWING MACHINE.

Application filed June 8, 1921. Serial No. 475,678.

To all whom it may concern:

Be it known that I, JOSEPH A. GROEBLI, a citizen of the United States, and a resident of the city, county and State of New York, have invented certain new and useful Improvements in Bead-Sewing Machines, of which the following is a specification.

My invention relates to that class of bead-sewing machines which may be designated as two-thread machines, that is machines whereby beads strung upon one thread are secured to a fabric by means of another or second thread; and my improvements are directed particularly to novel forms of mechanism adapted to accomplish this end; as I will now proceed to point out and explain.

In the drawings Fig. 1 is a side elevation of a machine embodying my invention; Fig. 2 is a similar view on an enlarged scale, and partly in vertical section, of the head, of the machine and of the operative parts carried thereby, some parts being omitted, for clearness, and a portion of the arm being broken away to condense the figure; Fig. 3 is a cross sectional view, also on an enlarged scale, and taken on the line 3-3 of Fig. 2, looking down; Fig. 4 is an end elevation, also on an enlarged scale, of parts of the mechanism, taken as looking to the right on Fig. 1; Fig. 5 is a side view of the bead separator and looper and of part of its shank; Fig. 6 is a plan view of the same; Fig. 7 is a cross sectional view of the concentric tubes, taken as on the line 7-7 of Fig. 2; Fig. 8 is a perspective view of the lower end of the bead and thread tube and its foot; Fig. 9 is a vertical, sectional view of the same and the separator, also showing the needle; Fig. 10 is a cross sectional view taken on the line 10-10 of Fig. 9, looking down; Fig. 11 is a detail of part of the feeding mechanism; and Fig. 12 is a cross sectional view of the same, taken on the line 12-12 of Fig. 11.

Figs. 5 to 10 inclusive are on a still further enlarged scale as compared with Figs. 2, 3 and 4.

The machine is provided with a base plate 1, and with a bracket 2, an arm 3 and a head 4 to support the mechanism in proper operative position above the base plate. And suitable brackets 5, 6, 7 and 8 are provided beneath the base plate for supporting the mechanism operating the needle and nipple and for controlling the direction of the feed.

The driving shaft 10, through beveled

gears 11 and 12, shown in broken lines in Fig. 1, drives the shaft 13, which through gears 14 and 15 turns the shaft 16, which through cam 17 operating against bell crank arm 18 rocks the bell crank, and causes its pin 19, engaging with the jaws 20 of the sliding nipple support 21, to raise and lower the nipple, and through wrist pin 22, operating in a cam groove in the needle carrier, raises and lowers the needle carrier in a manner heretofore disclosed in the art, and which for that reason I have not illustrated in further detail.

The shaft 10 carries a gear 30, meshing with a gear 31, which, in turn drives a gear 32 on shaft 33, the gear 31 being journalled on one end of a yoke 34, one arm of which is journalled on the end of the shaft 33, while the other end is journalled on the shaft 10 and is provided with a gear wheel 35, the function of which will be hereinafter explained.

The shaft 33 also carries a gear 36, meshing with a gear 37, on a tube 38 carried rotatably by a bracket 39 on the head of the machine, and telescoping within another tube 95 which, in turn, is supported rotatably in brackets 40, 41 on the head 4. The upper end of the tube 38 carries a bracket 42 which supports a thread reel 43, the stitching or back thread 44 from which is carried down within the tube 38, and out through a hole 45 in a collar 46 on the lower end of the tube 38. To the collar 46 is attached a shank 47, which carries the disk-like bead separator 48, which has a central opening 49, having an eccentrically formed extension 50 at one side, below which is a shelf 51, extending about one third of the distance around the central hole 49. The separator 48 has a thread guide hole 52, through which the thread 44 is led down to the needle.

A tube 53 is centered within the tube 38, with a free space between them, being carried by an extension 54 on the bracket 55 attached to the arm 3, and being centered at its lower end by passing through the collar 46 carried by the tube 38, a side opening 56 being formed near its bottom, and a guide foot 57, provided with a bead and thread opening 58, and with a needle opening 59, being attached to the lower end of the tube. The face thread 60 which is shown in Figs. 8 and 9, but, for clearness, not in Figs. 1, 2, and 3, is threaded through the beads 61, 61 110

and is wound, with the beads loosely strung upon it, on the reel 62, from which it is led down through the trough 63, past the bead feeders 64, 65, which are reciprocated respectively, through rod 66, attached to one arm of bell crank 67, the free end 68 of which rests against the eccentric 69 on the shaft 33, and through rod 70, attached to one arm 71, of a bell crank of which 72 is the hub, the other arm 73 of which bell crank bears against the opposite side of the eccentric 69, so that the feeders are rocked once with each revolution of the shaft 33 to pass one bead to the sprocket wheel 74. As this feeder mechanism is the subject of a separate application, Serial Number 445,943, filed February 18th, 1921, I will not more particularly describe it. As for the purposes of this application I simply desire to indicate mechanism whereby the beads may be fed forward to the separator.

From the sprocket wheel 74 the thread passes down through the tube 53 to its foot 57, and through it and the separator 48 to the fabric, one bead being allowed to pass the separator with each revolution of that element.

With each revolution of the driving shaft the needle 75 is reciprocated once; one bead is passed by the bead feeders and allowed to fall down through the tube 53 to the separator 48 or to the top of the column of beads resting upon it; one bead is passed by the separator as it revolves, and is allowed to slide down the thread 60 to the fabric, the eccentric inner edge of the separator cutting in between that bead and those above it, and preventing the latter from going on down; and, also, the thread 44 being thrown around the needle and around the thread 60, above the bead which has reached the fabric, so that, when the needle completes its stitch with the thread 44 the stitch will attach and hold the thread 60 and its bead securely to the fabric.

The direction in which the fabric is fed is governed in the following way. A control shaft 76 is mounted in suitable bearings in the frame of the machine, and may be rotated by a hand crank 77 in either direction. Upon the shaft 76 are mounted several spur gears 78, 79, 80 and 81 meshing, respectively, with spiral gears 82, on shaft 86, 83 on shaft 87, 84 on shaft 88, and 85 on shaft 89, each of which shafts is journaled in suitable bearings in the frame of the machine.

The shaft 86, through crown gear 90, and crown gear 91 mounted on a sleeve 92, within which the needle carrier is splined, rotates the needle carrier in either direction as desired.

The shaft 87, through crown gear 93, and crown gear 94 on the upper end of tube 95, rotates that tube in either direction, causing

it to carry around with it the foot 96 which is attached to the collar 97, fastened to the lower end of the tube by suitable means, such as set screws 98, 98.

The shaft 88, through crown gear 99, and crown gear 100, turns shaft 101, on which, is mounted a collar 117 in bearings in which is pivoted a lever 103.

A cam 107 on the shaft 33, rocks a bell crank 108, causing its arm 109 to press down a pin 110 on a bar 111 sliding in the head of the machine, the bar being raised again by a spring 112. The bar 111 carries a forked arm 113 in which the sleeve 114 may revolve. In this sleeve is formed a grooved seat 115, in which rests end 116 of lever 103, which is pivoted in the collar 117 keyed on the shaft 101. The shank of this collar 117 passes through an elongated, rectangular opening in a disc 118 mounted rotatably in the extension 104 of the feeder bar 105.

The lower end of the lever 103 rests in a socket in the disc 118, and springs 119 hold the disc and collar normally in the positions shown in Fig. 12. When, therefore, the shaft 101 is rotated it carries around with it the collar 117, and when the sleeve 114 is pushed down it will, through the lever 103 swing the disc, extension and feeder bar with the feed foot 106 in the proper direction to accomplish the desired feeding operation.

The raising and lowering of the feeder bar 105 is accomplished through bell crank 67 raising an arm 123 on a slide 124 in the head of the machine, which slide carries an arm 125 having a block 126 pivoted thereto and sliding on the tube 38, to which block the feeder bar is also pivoted, so as to be raised and lowered thereby. The slide may be depressed by any suitable means, such, for instance, as a spring 127.

The general features of this feeding mechanism are understood by those acquainted with the prior art and they are simply shown herein to illustrate a type of operative mechanism to which my direction governing mechanism may be applied.

The shaft 89, through crown gear 120 and crown gear 121 on tube 53 turns that tube, 115 and with it its foot 57, to the same extent and in the same direction as the other two tubes and the needle are turned.

In order, however, that the proper relation may be maintained between the separator 48, 120 foot 57, foot 96, the needle and the direction of feed, it is requisite that the extent of the rotation of the separator relative to the other elements shall be augmented or diminished to correspond with the extent of the forward 125 or backward movement of the other cooperating elements. That is the cycle of operation of the bead delivering and stitch forming means, which may be called a stitch cycle, must be adjusted to correspond ac- 130

curately with the angular change in the direction of feed.

This is accomplished by securing upon the shaft 87 a gear wheel 122 of half the size of 5 and meshing with the gear 35. So that when the shaft 87 is turned, the yoke 34 will be also turned, to one half of the same extent, but as the turning of the yoke 34 causes its gear 31 to run ahead of or lag behind the gear 30, while the gear 32 is moved forward or back an equal relative distance, the result will be that the shaft 33 will be given an additional forward movement equal to the forward movement of the gear 35, or its 15 movement will be diminished to an extent equal to the backward movement of the gear 35, the total movement being equal to that of shaft 87.

By these means I secure a machine which, 20 by a continuous rotation of the separator attaches the face or bead thread and beads securely to the fabric, which, as compared with a one thread machine, is advantageous, because if one thread should break the second thread will, to a large extent, hold the 25 beads in place. Besides, it permits of stringing the beads much closer together upon the bead thread, as only sufficient space need be left between the beads for their proper spacing upon the fabric and to permit of the locking thread being cast around the bead thread after each stitch. This is a decided 30 advantage in practice.

Also the direction of the feed may be governed by a single controlling element, as the hand crank 77, so that the cooperating parts will all retain their proper relative positions and will function correctly as the feed is varied, there will be no irregularities in 35 the work nor any interruptions nor complications in the operation of the machine.

While I have described the separator as passing one bead at a time, it should be understood that if it is desired to pass more 40 than one bead at the same time that may be done, if the beads are sufficiently short so that two or more will be passed together by the separator; or, the separator may be so proportioned as to normally pass more than 45 one bead; it being understood that at each revolution the separator will pass a predetermined number of beads whether one or more.

I wish it to be understood that details of 50 my improvements may be varied, as by the use of mechanical equivalents or the like, without departing from the spirit of my invention as described and claimed.

Having thus described my invention, what 55 I claim, and desire to secure by Letters Patent of the United States is:—

1. The combination, in a bead sewing machine, of means for holding a supply of beads slidably upon a bead thread, means 60 for applying a stitching thread, and means

for feeding the beads along the bead thread and also for winding the stitching thread around the bead thread.

2. The combination, in a bead sewing machine, of means for holding a supply of 70 beads slidably upon a bead thread, means for applying a stitching thread, and means for feeding the beads along the bead thread and also for winding the stitching thread around the bead thread after each stitch. 75

3. The combination, in a bead sewing machine, of means for holding a supply of beads slidably upon a bead thread, means for applying a stitching thread, and means for feeding a predetermined number of 80 beads along the bead thread after each stitch and also for winding the stitching thread around the bead thread.

4. The combination, in a bead sewing machine, of means for holding a supply of 85 beads slidably upon a bead thread, means for applying a stitching thread, and rotatable means for feeding the beads along the bead thread and means for winding the stitching thread around the bead thread. 90

5. The combination, in a bead sewing machine, of means for holding a supply of beads slidably upon a bead thread, means for applying a stitching thread, and continuously rotatable means for feeding the 95 beads along the bead thread and means for winding the stitching thread around the bead thread.

6. The combination, in a bead sewing machine, of means for holding a supply of 100 beads slidably upon a bead thread, means for applying a stitching thread, and unitary means for feeding the beads along the bead thread and also for winding the stitching thread around the bead thread. 105

7. The combination, in a bead sewing machine, of means for holding a supply of beads slidably upon a bead thread, means for applying a stitching thread, and means for feeding the beads intermittently along 110 the bead thread and also for winding the stitching thread around the bead thread.

8. The combination, in a bead sewing machine, of means for supplying a thread carrying strung beads to a fabric, bead feeding means, and means embodying looping means for casting a stitching thread over the bead carrying thread, such feeding means and looping means being embodied in a unitary and continuously rotating element. 115

9. The combination, in a two thread sewing machine, of concentrically arranged thread and bead supplying means, unitary bead separating means and thread looping means, and fabric downhold means, and needle reciprocating means. 125

10. The combination, in a two thread bead sewing machine, of thread and bead supplying means, unitary bead separating and thread looping means, and fabric down- 130

hold means, such several means being carried by concentrically arranged, relatively rotatable tubes, and needle reciprocating means.

11. The combination, in a sewing machine embodying fabric feeding means, means for supplying a face-thread, bead supplying means, bead separating means, and means, embodying a continuously rotatable looper and a reciprocating needle, for applying a stitching thread, of means for changing the direction of feed and means for correspondingly changing the stitch cycles of the looper and of the bead separating means.

12. The combination, in a sewing machine embodying rotatable fabric feeding means, rotatable means for supplying a face-thread, bead supplying means, bead separating means, and means, embodying a continuously rotatable looper and a rotatable reciprocating needle, for applying a stitching thread, of means for changing the direction of feed and means for correspondingly changing the stitch cycles of the looper and of the bead separating means.

13. The combination, in a sewing machine embodying fabric feeding means, means for supplying a face-thread, bead supplying means, bead separating means, and means, embodying a continuously rotatable looper and a reciprocating needle, for applying a stitching thread, of rotatable means for changing the direction of feed and rotatable means for correspondingly changing the stitch cycles of the looper and of the bead separating means.

14. The combination, in a sewing machine embodying fabric feeding means, face-thread, supplying means, bead supplying means, bead separating means, and back-

thread looping and stitching means, of means for varying the direction of feed, and automatic means for simultaneously lengthening or shortening the cycles of operation of the looping and stitching means and of the bead separating means.

15. The combination, in a sewing machine embodying fabric feeding means, face-thread and bead supplying means, bead separating means, and back-thread looping and stitching means, of means for varying the direction of feed, and automatic means for simultaneously extending or diminishing the cycle of operation of the looping and stitching means.

16. The combination, in a sewing machine embodying fabric feeding means, face-thread and bead supplying means, bead separating means, and back-thread looping and stitching means, of means for varying the direction of feed and point of bead delivery, and automatic means for simultaneously lengthening or shortening the cycle of operation of the looping and stitching means.

17. The combination, in a sewing machine embodying fabric feeding means, bead supplying means, bead separating means, stitch forming means, the bead separating and stitch forming means normally operating in a cycle of three hundred and sixty degrees, means for adjusting the feeding means around the circumference of a circle to vary the direction of feed, and automatic means for correspondingly extending or diminishing the cycle of operation of the bead separating means and of the stitch forming means.

JOSEPH A. GROEBLI.
